CHARLES MACKENZIE ABERCROMBIE, OF BRIDGEPORT, CONNECTICUT,
ASSIGNOR TO WHEELER & WILSON MANUFACTURING COMPANY, OF
BRIDGEPORT, CONNECTICUT, A CORPORATION OF CONNECTICUT.

HEMSTITCH SEWING-MACHINE.

SPECIFICATION forming part of Letters Patent No. 724,233, dated March 31, 1903.

Application filed April 24, 1902. Serial No. 104,543. (No model.)

To all whom it may concern:

Be it known that I, CHARLES MACKENZIE ABERCROMBIE, a citizen of the United States, residing at Bridgeport, in the county of Fairfield and State of Connecticut, have invented a certain new and useful Improvement in Hemstitch Sewing-Machines, of which the following is a full, clear, and exact description.

This invention relates more particularly to 10 that class of sewing-machines for hemstitching fabrics wherein two forward feed movements of the material alternate with one backward feed movement, the needle being vertically actuated after each feed movement 15 and having lateral movements timed alternately to place two stitches off of the fold or hem and one on, as common in the formation of a hemstitch-seam.

The object of the invention is to combine 20 a piercer with the needle and actuate the two simultaneously, while retaining the independent oscillating motion of the needle, thereby dispensing with an independent piercer-bar.

25 In carrying out the invention there is employed a vertically-reciprocating needle-bar to which in addition is imparted an oscillating movement, the said needle-bar having applied to it a tubular bar, to which the piercer is attached, the said piercer-carrying bar partaking of the reciprocating motion of the needle-bar, but without receiving its oscillating motion. The piercer is adjustable, so as to bring it in proper relation and alinement with 35 the needle, all as will be hereinafter more particularly set forth and finally claimed.

In the accompanying drawings, illustrating the invention, in the several figures of which like parts are similarly designated, Figure 1 40 is a front elevation of a Wheeler & Wilson vertical-hook machine, the face-plate being removed and the arm in partial vertical section. Fig. 2 is a perspective view of the needle-bar and piercer-bar disassembled. Fig. 3 45 is a perspective view of the cap-plate for the needle-bar. Fig. 4 is a perspective view of a ball-and-socket connection in the needle-oscillating mechanism, the parts being disassembled. Fig. 5 is a perspective view of the ad-

justable piercer-holder, the parts being dis- 50 assembled. Fig. 6 is a bottom plan view of the piercer-holder and the tubular bar to which it is attached.

Parts herein shown and not particularly de- 55 scribed may be of the usual or any approved construction, it being understood, as already indicated, that the material-feed mechanism is capable of imparting two forward feed movements of the material alternately with one backward feed movement. 60

1 is the bed-plate, and 2 the arm rising therefrom and containing in its upper horizontal portion the usual needle-actuating shaft 3, on the forward end of which is any usual or approved motion-transmitting de- 65 vice 4, such as a cam, crank, or disk.

5 is the needle-bar, the upper end of which is provided with a spline 6, having tubular collars 7 at opposite ends fitted to the needle-bar and secured thereto by means of screws 8. 70

9 is a sleeve provided with a longitudinal groove 10. This sleeve is arranged in a hole in the upper end of the arm 2, and within said sleeve is arranged the spline 6, said spline working within the slot 10 and its collar 7 fitting the bore of the sleeve with sufficient accuracy to prevent undue lateral vibration or trembling of the needle-bar. The upper end of the sleeve 9 is provided with a shoul- 75 dered head 11, which rests upon the top of the adjacent portion of the arm 2, and in order to prevent longitudinal movement of this sleeve and at the same time permit the axial movement thereof there is placed over said shouldered head a cap-plate 12, which is re- 80 cessed at 13, (see Fig. 3,) and this recess has a lateral opening 14. The cap-plate is secured to the overhanging arm by means of screws or other fastening devices passed through openings 15 in said cap-plate and en- 85 gaging the arm. The head of the sleeve is provided with a laterally-projecting arm 16, extending out of the opening 14 in the cap-plate, and this arm 16 is connected with a link 17, which in turn is jointed at 18 to a lever 19, pivoted at 20 to a portion of the arm, and said lever 20 is vibrated by a cam 21, 90 mounted on the arm and driven from the

95

shaft 3 in any suitable manner, said cam having a cam-groove 22, with which the lever 19 is connected by means of a roller-stud 23. Thus the sleeve, connected with the needle-bar as just described and operated as just stated, becomes, in effect, a vibrating gate for imparting the necessary oscillating motion to the needle-bar for hemstitching.

The needle 24 is mounted eccentrically in 10 a needle-holder 25, which is secured to the end of the needle-bar by a set-screw 26 or any other convenient device, and this needle-holder also serves the purposes of a collar, as will now appear.

15 A tubular bar 27 is applied to the lower end of the needle-bar 5 between the lower collar 7 of the spline 6 and the needle-holder 25, and by this collar and the said needle-holder the tubular bar 27 is held in position. This 20 tubular bar is provided at its upper end with a pinch-clamp 28, having a laterally-projecting pin 29, which is engaged by a link 30, connected with the device 4 for imparting vertical reciprocating motion to the said tubular bar, which motion, as will be understood, is transmitted to the needle-bar. The lower end of this tubular bar is provided with a pinch-collar 31, from which depends an arm 32, the face of which is provided with a trans- 25 verse groove 33, pierced by a slot 34. 35 is the piercer-holder, having a transverse rib 36, adapted to fit adjustably in the groove 33 and secured in its adjustment by means of a set-screw 37, passed through the slot 34 and into 30 the holder 35, so that the said holder may be adjusted laterally with relation to its supporting-arm 32. 38 is the piercer, having the right-angle bend 39 and adapted to be inserted in the holder 35 and secured therein 35 by means of a set-screw 40 in such way that the piercer may be adjusted axially, as indicated by dotted lines in Fig. 6, and since the piercer is made with the bend 39 it is herein referred to as a "cranked" piercer.

40 A further and important feature of adjustment of which my construction is capable is the movement of the piercer in an arc of a circle having the needle-bar as its center. Independently of the adjustment of the piercer 45 toward and from the needle in the line of the seam said piercer is also adjustable transversely of the seam by rotating the pinch-collar 31 upon the tubular bar, and the effect of this transverse adjustment is to cause the 50 piercer to descend at any desired point with relation to the fold without interfering with the adjustment of the piercer in the line of the seam. In other words, the two adjustments of the piercer may be effected quite independently of one another, and this is a condition which is impossible in those constructions where the piercer-holder is adjustably supported independently of the needle-bar and out of substantial concentricity there- 55 with.

60 While it is desirable to have the piercer itself axially adjustable in order to increase

the range of production, the invention is not limited to such feature.

Any suitable connection may be made between the arm 16 and the link 17, and one preferred construction of such connection is shown in detail in Figs. 2 and 4, the same consisting of a screw-bolt 41, tapped in the arm 16 and held in adjusted position therein by 70 means of a set-nut 42. The end of this bolt is provided with a spherical head 43, and in order to provide a universal joint the link 17 may have its outer end provided with a socket member 44, the complementary socket member 45 being attachable by screws or otherwise to the socket member 44 with the head 43 of the screw-bolt between.

75 From the foregoing it will be clear that as the movement of the cam 21 is transmitted to the sleeve 9 the latter will cause the needle-bar to oscillate axially without interfering with the vertical reciprocation of said bar, the extent and time of such oscillation being primarily governed by the profile of said cam 80 and a slight variation in the extent of such oscillation being permissible by adjusting the screw-bolt 41.

85 By constructing the piercer and its holder as described the piercer is capable of two distinct adjustments in order to maintain the proper relative position of piercer and needle. The distance between the needle and the piercer must equal a multiple of the length of stitch or feed movement employed, and 90 when the latter is changed the position of the piercer must be made to correspond therewith, and this may be accomplished by loosening the piercer set-screw 40 and turning the piercer axially, as indicated by dotted lines 95 in Fig. 6, until its point is the proper distance in advance of the needle, after which the set-screw is tightened and the piercer-holder is shifted laterally through the medium of the set-screw 37 until the point of the 100 piercer is in proper alignment with the needle.

105 The construction herein shown and described as applicable to a Wheeler & Wilson vertical-hook machine is susceptible of structural changes as well for that machine as for 110 others, and what is herein shown and described is illustrative only of one and the present preferred form of the invention.

115 What I claim is—

1. In a sewing-machine of the class described, a needle-bar and needle, combined with a piercer-carrier comprising essentially a piercer-holder adjustable in the line of feed, and a holder-support connected with the needle-bar and adjustable circularly thereon 125 independently of the feed-line adjustment.

2. In a sewing-machine, a reciprocating and oscillating needle-bar, a needle, a piercer, a holder for said piercer having means to adjust said piercer toward and from the needle 130 in the line of feed, and a support for said holder mounted upon the needle-bar and adjustable concentrically thereon.

3. In a sewing-machine of the class de-

scribed, a piercer, a holder therefor having means to adjust the piercer axially and means to adjust it laterally with relation to the needle, and a tubular bar by which the 5 piercer-holder is carried, combined with a needle, a needle-bar upon which the tubular bar is mounted, a non-oscillating connection for the tubular bar with the needle-bar, and means for conjointly reciprocating the needle-bar and tubular bar.

4. In a sewing-machine, a needle-bar, a needle, an oscillating mechanism connected with said needle-bar, a tubular bar applied to said needle-bar, a piercer, a piercer-holder

15 adjustably secured to said tubular bar, and means connected with the tubular bar for imparting vertical reciprocation to the tubular bar and through it to the needle-bar, said piercer-holder capable of adjustment in the

20 line of the seam independent of its adjustment on the tubular bar.

5. In a sewing-machine, a needle-bar, means to reciprocate it longitudinally, a tubular bearing for one end thereof, connections between said bar and bearing for restraining axial movement of the bar, means to oscillate said bearing and through it the needle-bar, a tubular bar mounted upon the needle-bar and partaking of the longitudinal movement only of the bar, and a piercer-holder mounted 30 upon the tubular bar and having a piercer, whereby said piercer partakes of the longitudinal movements of the needle-bar while restrained from receiving its oscillating movements.

In testimony whereof I have hereunto set my hand this 23d day of April, A. D. 1902.

CHARLES MACKENZIE ABERCROMBIE.
